DISPENSER FOR TIE STRIPS OR THE LIKE

Gerald C. Bower, Santa Ana, and Wayne M. Becker,
Studio City, Calif., assignors to Royal Industries, Inc.,
Pasadena, Calif., a corporation of California

Filed Mar. 13, 1964, Ser. No. 78,994

Term of patent 14 years

(Cl. D52—1)

FIG. 1.

FIG. 2.

FIG. 3.

FIG. 4.

FIG. 5.

FIG. 6.

FIG. 1 is a top plan view of the dispenser for tie strips or the like showing our new design;

FIG. 2 is a front view of the dispenser as illustrated in FIG. 1;

FIG. 3 is an end view of the left side of the dispenser as illustrated in FIG. 1;

FIG. 4 is a bottom plan view of the dispenser for tie strips or the like;

FIG. 5 is a back view of the dispenser as shown in FIG. 1; and

FIG. 6 is an end view of the right side of the dispenser as illustrated in FIG. 1.

We claim:

The ornamental design for a dispenser for tie strips or the like as shown.
